D. LANGINGER

Des. 167,267

HAT

Filed April 20, 1951

FIG. 1.

FIG. 2.

Inventor

Dorothy Langinger

UNITED STATES PATENT OFFICE

167,267

HAT

Dorothy Langinger, Los Angeles, Calif.

Application April 20, 1951, Serial No. 14,904

Term of patent 14 years

(Cl. D3—13)

To all whom it may concern:

Be it known that I, Dorothy Langinger, a citizen of the United States of America residing in the city of Los Angeles, in the county of Los Angeles, State of California, have invented a new, original, and ornamental Design for a Hat, of which the following is a specification, reference being had to the drawing, forming a part thereof.

Fig. 1 is a top plan view of a hat, showing my new design; and

Fig. 2 is a perspective view thereof.

I claim:

The ornamental design for a hat, substantially as shown.

DOROTHY LANGINGER.
